UNITED STATES PATENT OFFICE

CHARLES M. CHRISTIAN, OF FONDA, IOWA

SANITARY SLEEVE FOR ICE CREAM AND OTHER CONTAINERS

Application filed February 20, 1931. Serial No. 517,321.

This invention relates to an adjustable sleeve for ice cream containers and the like, the general object of the invention being to provide a sleeve that is adapted to be placed in the upper part of a container after the contents have been partly removed therefrom, so that the paper or other lining of the container will be protected by the sleeve and the sleeve will act to prevent the upper part 10 of the lining from falling away from the sides of the container, said sleeve also acting to prevent the arm or sleeve of the person removing the contents from the container, from having his arm or sleeve soiled by some 15 of the contents of the container sticking to the upper part of the lining.

Another object of the invention is to make the sleeve in the form of a split sleeve and of flexible material so that the device can 20 be used on containers of different sizes, and also to provide the upper end of the device with a curved flange which is adapted to engage the upper edge of the container whereby the device is held in position.

25 This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several 35 views, and in which:—

Figure 1 is a longitudinal sectional view through an ice cream container showing the invention in use.

Fig. 2 is a section on the line 2—2 of Fig. 1. 40 Fig. 3 is a view of the device in flattened position.

Fig. 4 is a top plan view of the device.

In these drawings, the numeral 1 indicates the device which is formed of an elongated 45 sheet of any suitable material which when rolled into a sleeve or cylinder will retain this position while permitting the sleeve to be expanded or contracted so that it can be placed in different sizes of cans.

50 A rolled flange 2 is formed at the upper

edge of the device so that this flange will engage the upper edge of a container A when the device is placed in the upper part of the container as shown in Fig. 1. Thus the flange will hold the device in the upper part 55 of the container.

As is well known, containers for ice cream and the like are provided with a paper or other lining B which, when some of the contents are removed from the container will fall away from the sides of the container and thus make it difficult to remove the rest of the contents from the container and portions of the contents sticking to the upper part of the lining will soil the arm and sleeve 60 of a person dipping the rest of the contents from the container.

By placing this sleeve in the upper part of the container, after some of the contents have been removed, the sleeve acts to hold 70 part of the lining in place, and it also prevents the arm or sleeve of the user from coming into contact with the lining and thus prevents any of the contents sticking to the lining from soiling the arm or sleeve. 75

The sleeve also protects the upper part of the lining from dirt, dust, insects or the like, and as the lining is made in the form of a split sleeve having a certain amount of resiliency, the device can be placed in containers of different sizes.

It is thought from the foregoing description that the advantages and novel features of the invention will be readily apparent.

It is to be understood that changes may be 85 made in the construction and in the combination and arrangement of the several parts, provided that such changes fall within the scope of the appended claim.

Having thus described my invention, what 90 I claim as new is:—

Means for holding the top part of a lining of a container for ice cream and the like in position after some of the contents of the container have been removed, and for preventing the arm of a person removing the contents comprising a split sleeve of resilient and flexible material, fitting in the upper part of the container and within the upper part of the lining, and having a rounded 95 100

flange at its upper end fitting over the upper end of the lining and the container, said sleeve being of a length sufficient to extend well into the container to protect the arm or sleeve of a person removing the contents from the container.

5 In testimony whereof I affix my signature.

CHARLES M. CHRISTIAN.
